UNITED STATES PATENT OFFICE.

ARTHUR A. DIX, OF KANSAS CITY, MISSOURI.

DESIGN FOR A BADGE.

44,659.

Specification for Design.

Patented Sept. 16, 1913.

Application filed July 10, 1912. Serial No. 708,640½. Term of patent 3½ years.

To all whom it may concern:

Be it known that I, ARTHUR A. DIX, a subject of the King of England, residing at Kansas City, in the county of Jackson and State of Missouri, have invented a new, original, and ornamental Design for a Badge, of which the following is a specification, reference being had to the accompanying drawing, forming a part thereof.

The figure is a plan view of a badge, one feature of which is the representation, upon a back-ground, of a dog and of a foot in the act of kicking the dog, it being noted that the attitude of the dog is such as to in-

dicate that he is just leaving the ground under the force of the kick. Another feature of the design is a marginal panel underlying the dog and the foot.

I claim:

The ornamental design for a badge, as shown.

In testimony whereof, I affix my signature in the presence of two witnesses.

ARTHUR A. DIX. [L. S.]

Witnesses:

M. K. PRESTON,
G. Y. THORPE.
